VISIBLE SHIFT BINDER

John H. O. Kornahrens, Rego Park, N. Y., assignor
or to The C. E. Sheppard Co., Long Island City,
N. Y., a corporation of New York

Application July 29, 1937, Serial No. 156,286

1 Claim. (Cl. 129—17)

This invention relates to visible shift binders and has for an object to provide a binder of the above type having novel and improved details of construction and combinations of parts.

Various other objects will be apparent as the nature of the invention is more fully disclosed.

Although the novel features which are believed to be characteristic of this invention will be more particularly pointed out in the claim appended hereto, the invention will be better understood by referring to the following description, taken in connection with the accompanying drawing, in which a particular embodiment thereof has been set forth for purposes of illustration.

15 In the drawing:

Fig. 1 is a top plan view of the hinged back portion of a binder embodying the present invention;

Fig. 2 is a section taken on the line 2—2 of

20 Fig. 1;

Fig. 3 is a section taken on the line 3—3 of Fig. 1, but with the back in partly open position;

Fig. 4 is a section taken on the line 4—4 of Fig. 1, but with the back closed; and

25 Fig. 5 is a detail view of the slide.

In the following description and in the claim certain specific terms are used for convenience in referring to various details of the invention. It is to be understood, however, that these terms are to be given as broad an interpretation as the state of the art will permit.

Referring to the drawing more in detail, the binder is shown as having a channel back formed of two angle pieces 10 and 11, carrying Z-plates 12 and 14, respectively, which are permanently attached thereto in any convenient manner to form box-like structures. The Z-plates 12 and 14 are formed with sections 12a, 12b, and 12c and 14a, 14b, and 14c, respectively, which are disposed at right angles to each other and are positioned with the sections 12a and 14a adjacent and attached to the angle pieces 10 and 11, respectively. Hinge knuckles 15 and 16 are formed on the sections 12c and 14c and are joined by a hinge pin 17 to form a hinge about which the two angle pieces 10 and 11 can be opened. The section 14a of the Z-plate 14 carries a set of prongs 20 which are adapted to engage the perforations in the loose leaves, not shown. Section 14a also carries hinge knuckles 21 to which a cover 22 is hinged as by hinge pin 23.

A slide 25 is mounted adjacent the section 12a of the Z-plate 12 and carries prongs 26 which are similar to the prongs 20, above mentioned. 55 The slide 25 is provided with ears 27 which enter

elongated recesses 28 in the section 12b of the Z-plate 12. The slide 25 carries hinge knuckles 29 in alignment with hinge knuckles 30 formed on the section 12a of the Z-plate 12. The hinge knuckles 29 of the slide 25 are spaced to receive hinge knuckles 31 of a cover 32 therebetween, the hinge knuckles 29, 30 and 31 being secured by a hinge pin 33. The dimensions of the hinge knuckles 29 and 30 are such that clearance is provided between adjacent hinge knuckles of the slide 25 to permit a predetermined longitudinal movement thereof.

One of the ears 27 carries a channel member 35 which is disposed beneath the section 12b of the Z-plate 12 and is provided with a flange 36 disposed adjacent the section 12c and adapted to register with an aperture 37 in said section 12c when the slide 25 is not in normal operating position. A finger 40 is attached to the Z-plate 14 in a position to enter the aperture 37 above mentioned. The finger, however, is prevented from entering the aperture by the flange 36 of the channel member 35 except when the slide is in normal position, thereby preventing the back from being closed until the slide has been returned to said position.

Two position latches 41 are attached to the Z-plate 14 and are provided with pairs of catches 41a and 41b to hold the back in closed position as shown in Fig. 4, or in partly open position as shown in Fig. 3. A suitable lever 42 is provided for actuating the latches 41 to permit the back to be opened when desired.

It will be noted that in the above described construction the slide 25 is held in position by 35 ears 27 as well as by hinge pin 33 and channel member 35. This provides a plurality of sliding supports for the slide 25 which permit free sliding movement thereof and prevent the weight of the sheets carried on the prongs 26 from interfering with the operation thereof. Furthermore, the cover 32 is hinged between the hinge knuckles 29 of the slide 25 in such a way that the cover is shifted with the slide and prongs. Inasmuch as the pages are necessarily shifted with the prongs, 45 this prevents relative movement between the pages and the cover.

The channel member 35 is welded or otherwise permanently secured to the ear 27 so that the slide cannot be removed after the binder has been 50 assembled. The channel member prevents the slide from becoming displaced when the hinge pin 33 is removed. This piece 35 also serves as a stop to prevent the binder from being closed when the prongs are improperly positioned and 55

also prevents the prongs from being shifted longitudinally of the back when the binder is in closed position.

While a specific embodiment of the invention has been shown for purposes of illustration, it is to be understood that the invention is capable of various uses and that various changes and modifications may be made therein as will appear to a person skilled in the art. The invention is only to be limited in accordance with the following claim when interpreted in view of the prior art.

What is claimed is:

A loose leaf binder, comprising a frame having two hinged parts, a box forming plate attached to each of said parts, hinge knuckles carried by one of said box forming plates, a slide mounted on said one of said plates and having hinge knuckles in alignment with the hinge knuckles

thereof and spaced to permit relative sliding movement therebetween, a cover having hinge knuckles positioned between the hinge knuckles of said slide and a hinge pin extending through all of said hinge knuckles to hingedly secure said cover to said slide and to slidably secure said slide to said part, one of said plates carrying a tongue adapted to enter an aperture in the other of said plates, an ear on said slide extending through an elongated slot in the corresponding plate and a member carried by said ear having a surface engaging said plate to secure said slide in position and having a flange registering with said aperture to prevent said tongue from entering the same except when said slide is in normal position.

JOHN H. O. KORNAHRENS.
